REFRIGERATING APPARATUS

Carl F. Petkowitz, Dayton, Ohio, assignor to General Motors Corporation, Dayton, Ohio, a corporation of Delaware

Application October 7, 1944, Serial No. 557,567

2 Claims. (Cl. 20—35)

1

This invention relates to refrigerator cabinets and particularly to a door construction for such cabinets.

While I am aware of the fact that many different seals and arrangements for securing the seal to a door of a refrigerator cabinet for sealing engagement with the cabinet are in existence, these known structures are not entirely satisfactory. Some of these door structures are complicated and expensive to manufacture and the arrangements for locking or securing a seal thereto have various disadvantages. For example, refrigerator cabinet doors having a seal extending therearound and secured thereto at spaced apart points by screws or other securing means necessitate punching of a plurality of holes along the seal through which the screws may pass. Due to variations in the distance between the holes punched in the seal and also variations in the distance between holes in the door walls or pans, the seal buckles intermediate certain screw holes and is stretched intermediate certain other screw holes. This prevents the seal from lying uniformly flat around all sides of the door and necessitates tightly latching the door to the cabinet, in order to properly seal entirely around the door opening, and thereby places undue pressure on the seal which shortens its life. In addition to this difficulty, it has been found that the cost of producing such seals can be greatly reduced by eliminating the operation of punching holes therein.

One of the objects of my invention is to improve and simplify the construction and assembling of a refrigerator cabinet door to thereby reduce manufacturing costs while at the same time increasing the structural strength of the simplified door construction.

Another object of my invention is to provide an improved method of and construction for locking a seal element to a refrigerator cabinet door.

A further object of my invention is to secure walls of a refrigerator cabinet door together at a point adjacent a seal on the door and to provide an arrangement for locking the seal upon the door solely by walls thereof in a manner to cause the seal to lie uniformly flat against the door entirely therearound to cause the seal to engage the cabinet with substantially the same sealing pressure throughout the distance around its door opening.

More specifically, my invention contemplates the locking of a seal against accidental removal from a refrigerator cabinet door, without passing screws or other securing means therethrough,

2

by a novel clamping or securing together of walls or elements of the door and to arrange the seal, with respect to the clamping or securing means, so that a portion thereof conceals the door wall clamping or securing together means from view.

Further objects and advantages of the present invention will be apparent from the following description, reference being had to the accompanying drawing, wherein a preferred form of the present invention is clearly shown.

In the drawing:

Fig. 1 is a front view of a refrigerator cabinet having my invention embodied therein and showing a portion of the cabinet door broken away;

Fig. 2 is a fragmentary enlarged cross-sectional view taken on the line 2—2 of Fig. 1; and

Fig. 3 is a fragmentary enlarged view of an inner-edge portion of the refrigerator cabinet door taken on the line 3—3 of Fig. 2.

Referring to the drawing, for illustrating the invention, I have shown in Fig. 1 thereof a refrigerator cabinet of the household type generally designated by the reference character 10. Cabinet 10 includes a metal exterior shell or panel 11 and an interior metal liner 12 forming walls of a food storage compartment or chamber 13 within the cabinet. Any suitable or desirable insulating material 14 is disposed between the liner 12 and walls 11 of the cabinet (see Fig. 2). An evaporator or cooling element 15 of a conventional refrigerating system is mounted in the upper part of compartment 13 for cooling and causing circulation of air therein. A frameless door, generally represented by the reference character 16, normally closes an opening in the front wall of cabinet 10 and provides access to the interior of food storage compartment 13. A door 17 may close or cover another opening in the front wall of cabinet 10 leading to a compartment which houses the refrigerating mechanism operatively connected with evaporator 15. The food compartment door 16 is provided with a seal element adapted to engage the front wall of cabinet 10 about the access opening of food compartment 13 and my invention is particularly directed to this element and the method of securing or locking same upon the door structure 16.

In the present disclosure, door 16 comprises a sheet metal wall forming member 21, shaped to provide the front face or wall and sides of the door, a non-metallic pan or wall forming member 22 shaped to provide the inner-wall of the door and suitable insulating material 23 disposed in the chamber therebetween (see Fig. 2).

A flange 24 is turned inwardly on the sheet metal member 21 from the sides thereof in spaced relation to the front face of door 16. This flange 24 is depressed or dented inwardly in a direction toward the front of door 16, as at 25 and 26, to provide walls of a groove or channel 27 extending around the inner-face of door 16 adjacent the sides thereof. The channel 27 in addition to increasing the structural strength of door 16, after assembly of elements thereof together, also prevents twisting of the door member 21 during the process of baking a vitreous enamel coating thereon. Furthermore, the channel 27 in door member 21 provides a countersunk mounting space for receiving a portion of a seal to be attached to the door 16. The inner pan member 22 of door 16 may be formed of any suitable insulating material such as the glass-like polystyrene moulded from a powder obtainable on the market under the name "Styron." This door pan member may be painted to match the color of the interior finish of the food storage compartment 13. Door pan member 22 is provided with a flange 28 which terminates in a bent edge portion 29 disposed within the channel 27 formed in flange 24 of a door member 21. The flange 28 on door member 22 registers with or abuts against the innermost portion of flange 24 on door member 21 to form the closed chamber in which the door insulation 23 is disposed. A plurality of securing means such as screws 31, preferably of the self-tapping variety, pass through holes provided in the flange 28 of pan member 22 and thread themselves into holes provided in door member 21 to secure the door wall forming members 21 and 22 in assembled relation to one another. The screws 31 are arranged in spaced apart relation, as shown in Fig. 3 of the drawing, around all sides of the door 16.

An extruded rubber or the like seal or seal element secured to the peripheral inner portion of door 16 includes a hollow resilient bead or cushion portion 35 adapted to sealing by engaging the metal cabinet wall 11 at the front of the cabinet around the food compartment access opening closed by door 16. The seal element also includes a compressible portion 36 formed integral with the cushion portion 35 thereof and disposed within the confines of the channel 27 around the door. Portion 36 of the seal element is formed into a hook-like shape in cross section for a purpose to be presently described. The seal element furthermore, includes a flexible lip portion 37, extending laterally from the sealing bead or cushion portion 35 thereof, and lying over the flange 28 and consequently the heads of screws 31 to conceal them from view.

In assembling the door structure of the present disclosure, the seal element is placed in position around the door member 21 with the hook-like portion 36 thereof disposed in the channel 27. The flexible lip 37 of the seal element is bent back over the cushion portion 35 thereof and the door pan 22 is placed in cooperation with the door member 21 with the flanges 24 and 28 registering with one another and with the insulating material 23 disposed in the chamber between the door wall forming members. The screws 31 are placed in position to firmly secure the flanges 24 and 28 and consequently the door members 21 and 22 respectively together. Lip 37 on the seal element is then released and its resiliency causes it to move against the flange 28 on pan member 22 to thereby cover and conceal the heads of screws 31. It is to be under-

stood that during the assembly of pan member 22 upon member 21, the edges 29 of pan member 22 are slipped or moved into the groove or opening of the hook-like portion 36 of the seal element. This locks the seal element upon the door and the edge portion 29 of pan member 22 is tightly compressed, by the screws 31, against the hook portion 36 of the seal element to thereby prevent removal thereof from the channel 27.

It will be seen that I have provided a simplified refrigerator cabinet door construction and have provided a novel structure for and method of clamping a seal element thereto without the necessity of passing screws or other securing means through the element. By virtue of the improved construction, the securing means for the sealing element and for the door pan members are concealed to thereby render the door neat in appearance. My improved construction eliminates buckling and/or stretching of the seal element at certain points around the door and permits the seal to lie uniformly flat against the inner-face of the door so that all portions of the seal will engage the front of the cabinet with substantially the same sealing pressure entirely around the door opening. Also by virtue of the depression in the flange on the metal door pan or member, the structural strength of the simplified construction is materially increased to thereby render it unnecessary to provide other or additional metal re-enforcing or frame forming elements within the door structure.

While the form of embodiment of the invention as herein disclosed constitutes a preferred form, it is to be understood that other forms might be adopted, as may come within the scope of the claims which follow.

What is claimed is as follows:

1. A door for a refrigerator cabinet comprising, an inner wall forming member and an outer wall forming member providing a chamber therebetween, insulating material within said chamber, said outer member having a flange portion thereon extending inwardly from sides of the door in spaced relation to the front thereof, said inner member having a flange portion thereon overlapping and abutting the flange portion on said outer member, means for securing the overlapping and abutting flange portions in direct contact with one another, a seal element for said door including a resilient sealing portion adapted to engage the cabinet and an integral mounting portion abutting said flange portion on said outer member, said seal element having a hook-like part formed in the mounting portion thereof, said flange portion on said inner wall forming member having an offset peripheral part substantially conforming to and fitting over said hook-like part of said seal element, and said securing means engaging said members to clamp said seal element mounting portion therebetween whereby said seal element is locked to the door.

2. A door for a refrigerator cabinet comprising, an inner wall forming member and an outer wall forming member providing a chamber therebetween, insulating material within said chamber, said outer member having a flange thereon extending inwardly from sides of the door in spaced relation to the front thereof, said flange having a portion intermediate the edge thereof and a side of the door depressed in a direction toward the front of the door to provide a channel around said door, said inner member having a flange thereon overlapping and abutting that portion of the flange on said outer member inwardly

of said depressed channel, means for securing the overlapping and abutting flange portions of said members in direct contact with one another, a seal element for said door including a resilient sealing portion adapted to engage the cabinet and an integral mounting portion disposed in the channel around said door, said seal element having an inwardly directed hook-like part formed in the mounting portion thereof, said flange on said inner wall forming member having a periph-

eral part offset toward the base of said channel substantially conforming to and fitting over said hook-like part of said seal element, and said securing means engaging the flange portion of said members inwardly of said depressed channel to clamp said seal element mounting portion in the channel whereby said seal element is locked to the door.

CARL F. PETKWITZ.
